(57) **CLAIM**

The ornamental design for an electric motor part, as shown and described.

DESCRIPTION

FIG. 1 is a front, bottom and right side perspective view of an electric motor part in accordance with the present design.

FIG. 2 is front elevation view thereof.

FIG. 3 is a right side elevation view thereof.

FIG. 4 is a rear elevation view thereof.

FIG. 5 is a left side elevation view thereof.

FIG. 6 is a bottom plan view thereof; and,

FIG. 7 is an enlarged top plan view thereof.

Elements drawn in broken lines in FIG. 7 represent aspects of the electric motor part which form no part of the claimed design.
